CONTAINER

Emery C. Furrer, Chicago, Ill.

Application March 20, 1937, Serial No. 132,061

6 Claims. (Cl. 206—44)

This invention relates to improvements in containers, particularly containers used for holding commodities, such as berries or other small fruits, for example.

5 An object of the invention is to provide an improved container having transparent walls as the sidewalls and bottoms, for example, whereby a customer can readily determine the condition of the contents which are hidden by the upper 10 layers thereof.

A specific object of the invention is to provide 15 a box such as a berry box having transparent walls formed of transparent or semi-transparent materials, such as "cellophane", waxed paper, or the like, and corner posts which may be formed of thin wood but preferably are formed of cardboard or heavy paper, and a wire reinforcing member which stiffens the structure and defines the lower corners of the containers and which 20 does not appreciably lessen the visibility of the lower contents of the box. While the use of transparent materials in walls of containers has heretofore been proposed, it is novel insofar as I am aware to utilize a simple wire stiffening 25 member which coacts with the vertical corner structure of the containers and also cooperates with the transparent sheet material to provide adequate visibility of the lower contents for inspection purposes.

30 Another object of the invention is to provide a box structure of the character mentioned having integral transparent walls which are so formed as to provide for ventilation of the contents and which will permit excess moisture to 35 drain from the box.

Other objects and advantages of the present invention will be apparent from a consideration of the following specification and accompanying drawing, wherein

40 Fig. 1 is a perspective view of a container embodying the present improvements;

Fig. 2 is a vertical section taken on line 2—2 of Fig. 1;

Fig. 3 is a broken sectional view through an 45 upper side portion of the container illustrating a loose cover attached to the container construction;

Fig. 4 is a top plan view of a corner portion of a wire frame;

50 Fig. 5 is a broken horizontal section through a container illustrating a modified construction;

Fig. 6 is a side elevation of the structure shown in Fig. 5;

55 Fig. 7 is a top plan view of the corner portion of a modified form of wire frame;

Fig. 8 is a side elevation of the frame shown in Fig. 7; and

Fig. 9 is a development of the receptacle or commodity-holding portion of the container.

In the drawing, the invention is shown as being embodied in a box such as is suitable for holding berries or other fresh fruit or like commodities. The container comprises an upper frame portion indicated generally by the numeral 10 which extends around and defines the 10 upper margin of the box. The member 10 is provided with legs 11 depending therefrom and which may, if desired, be integral with the member 10 as shown in the drawing. The member 10 and legs 11 may be formed of any suitable 15 sheet material such as cardboard, for example, and may be formed of a single piece of material, the ends of which may abut as shown at 12 in Fig. 1 or at any other suitable position.

The legs 11 may be scored along their vertical 20 center line so as to fold readily as shown in the drawing whereby approximately one-half of each leg overlaps a portion of the side wall of the container. The lower ends of the legs are preferably reduced in their horizontal dimensions as 25 shown for a purpose to be referred to later. Where the container is rectangular in cross section as shown, a similarly shaped lower wire frame 13 is provided which is disposed substantially in the plane of the bottom of the container. 30 The frame 13 is provided for stiffening or reinforcing purposes with loop formations 14 at its corners which engage the reduced lower portions of the legs to stiffen and support the same. As shown in Figs. 1 to 4, this loop formation is 35 integral with the adjacent sides of the frame and provides an L-shaped recess 15 which accommodates the lower ends of the legs as above stated.

Disposed beneath the wire frame member 13 40 is a bottom member 16 of sheet material and preferably transparent. The bottom 16, as shown in Fig. 9, is provided with panel-like extensions 17 at its several edges which are indicated by dotted lines 18, which panels, when the 45 same are folded upwardly, constitute the side walls of the receptacle portion of the container or box. The bottom 16 is disposed beneath the frame 13 as described while the panels 17 extend upwardly on the exterior of the frame and 50 are attached to the upper frame 10. The upper edges of the panels may be folded over the upper edges of the frame 10, after which a reinforcing marginal strip 19 may be positioned as shown in Figs. 1 and 2 and the parts thus assembled 55

secured together by staples 20 or other suitable fastening means. It will be seen that the panels 17 which constitute the side walls of the receptacle portion of the container overlap the adjacent portions of the respective legs 11 and preferably are not secured to said legs so as to provide a space through which air may circulate to some extent and through which excess moisture which may tend to collect in the box may 10 escape.

It will be noted that the panels 17 are of less horizontal length than the sides of the frame 12 and that small openings 21 are provided at the corners of the bottom 16 through which air 15 may enter for ventilation purposes and through which excess moisture may also escape from the box.

The wire frame 13 in the form shown in Figs. 1 to 4 preferably is of a single piece of material 20 and may have its ends connected together as at 22 either by soldering, welding or any other suitable manner. The box shown is of economical construction and likewise sturdy since the angular-shaped legs, reenforced and held in position 25 by the wire frame 13, provide a rigid structure.

In the modification of the invention shown in Figs. 5 and 6, the wire frame indicated generally by the numeral 13a may be formed of four pieces of wire shaped as shown in Fig. 5 and secured together as at 23 by welding, soldering or other approved means. Where this type 30 of construction is employed, the legs 11a are provided with openings 11b through which the ends 13b of the frame sections can be passed, after 35 which they are folded over into the position shown in Fig. 5. In Figs. 5 and 6, the other parts of the container are given reference characters corresponding to those used in Fig. 1 with the exponent *a*.

40 In Figs. 7 and 8, a wire frame 24 is shown which is somewhat similar to the frame shown in Figs. 1 to 4 in that the side portions of the same may be formed of a single piece of wire. The frame shown in Figs. 7 and 8 instead of having the interlocking arrangement shown in Fig. 4 is provided with substantially vertically disposed loop portions 25 and horizontal loop portions 26 which provide an L-shaped space 27 for 45 accommodating the lower portions of the legs of the container.

50 Covers for the containers may be provided, if desired, in which case, the same will be made preferably of transparent material of the type of which the bottom and side walls of the container are formed. The covers may be secured to the one side of the upper portion of the container as beneath the reenforcing band or strip 19. Such a cover 28 is shown in broken sectional view in Fig. 3.

60 Other constructions of the wire frames will occur to those skilled in the art as well as various modifications of the other specific features of the invention above described and shown in the drawing and I, therefore, do not wish to be restricted specifically to the embodiments of the invention herein shown and described except as so limited by the appended claims.

65 1. A container comprising an upper marginal member of sheet material, corner legs depending from said member, a transparent member sup-

ported by said marginal member and constituting the bottom and side walls of the receptacle portion of the container, and a wire member disposed within said receptacle portion at the perimeter of the transparent bottom thereof and provided with corner portions on the exterior of said receptacle engaging said legs. 5

2. A container comprising an upper marginal member of sheet material, corner legs depending from said member, a transparent receptacle 10 member having side walls secured to said marginal member and a bottom disposed within the confines of said legs, and a reinforcing member having a loop portion shaped in correspondence with said bottom and disposed at the upper margin 15 of said bottom and provided with portions disposed outwardly of said receptacle member each in engagement with one of said legs.

3. A container comprising a supporting frame 20 of sheet material having an upper rectangular marginal portion and depending corner legs, a receptacle portion of sheet material comprising a rectangular bottom disposed adjacent the lower ends of said legs and provided with side walls secured to said upper marginal portion of the 25 frame, and a rectangular stiffening member of loop form shaped in correspondence with said bottom and disposed within the receptacle portion at the margin of the bottom and attached at the corners thereof to the respective legs. 30

4. A container comprising a supporting frame of sheet material comprising an upper rectangular marginal portion and depending corner legs a receptacle portion of sheet material comprising a rectangular bottom disposed between the lower 35 portions of said legs and integral upwardly directed side walls secured to said marginal portion of said frame, and a rectangular member disposed within the receptacle portion at the margin of the bottom and provided with corner portions 40 engaging and supporting the lower portions of the respective legs.

5. A container comprising a frame of sheet material comprising an upper rectangular marginal portion and depending corner legs of angular 45 shape in cross section defining the vertical corners of the container, a receptacle portion of sheet material comprising side walls secured to said marginal portions of the frame and a rectangular bottom each edge of which is integral 60 with one of said side walls, and a wire reenforcing member disposed within the receptacle at the margin of said bottom and provided with loop-like portions extending between contiguous edges of adjacent side walls into engagement with the 55 respective legs.

6. A container comprising an upper frame of sheet material comprising an upper rectangular marginal portion and depending corner legs of angular shape defining the vertical corners of the 65 containers, a lower rectangular wire frame having corner formations engaging said legs adjacent the lower ends thereof, and a receptacle member of sheet material comprising a rectangular bottom disposed beneath said wire frame and integral side wall panels overlapping adjacent portions of said legs and extending to and connected with said upper frame.
